LIGHT-OPERATED SWITCH HOUSING

Clifford E. Myers, Forest Grove, Oreg., assignor to The Welsh Corporation, Longview, Wash.
Filed Apr. 20, 1970, Ser. No. 22,506

Term of patent 14 years

Int. Cl. D13—03

U.S. Cl. D26—13

FIG. 1 is a perspective view of a light operated switch housing as contemplated by the invention;

FIG. 2 is a side view taken generally from the right side of the FIG. 1, the opposite side having an appearance which is a mirror image of the side shown in FIG. 2;

FIG. 3 is a front elevation;

FIG. 4 is a back elevation; and

FIG. 5 is a top plan view.

I claim:

The ornamental design for light-operated switch housing, as shown and described.
